CIRCUIT PROTECTION

Original Filed Aug. 24, 1925

Inventor:
Josef Biermanns,
by Alexander S. Lunt.
His Attorney.

UNITED STATES PATENT OFFICE

JOSEF BIERMANNS, OF KARLSHORST, GERMANY, ASSIGNOR TO GENERAL ELECTRIC COMPANY, A CORPORATION OF NEW YORK

CIRCUIT PROTECTION

Application filed August 24, 1925, Serial No. 52,143, and in Germany September 16, 1924. Renewed April 18, 1930.

My invention relates to circuit protection, and more particularly to improvements in protective systems and apparatus for controlling an electric circuit on the occurrence of 5 abnormal conditions with a discriminating action dependent on the impedance and more particularly the reactance or the resistance component of the impedance potential drop of the circuit to be protected whereby a faulty 10 portion or section thereof can be disconnected selectively without interrupting continuity of service on the remainder of the circuit.

In a faulty line or circuit, the ratio of the potential to the current increases continuously from the point of fault to the source, since the potential e is smallest at the point of fault and largest at the source while the current i is the same at all points. Relays which operate when this ratio falls 20 below a certain value are known and by taking into consideration the resistances, reactances or impedances of the individual sections of the system, this value can be selected so that the circuit interrupting means 25 nearest the fault on each side thereof are actuated with reasonable certainty. It is difficult, however, perfectly accurately to adjust the relay and accurately to maintain this adjustment. If the adjustment is made for 30 too low an ohmic value, a line section subjected to a fault such as a short-circuit may not be disconnected while if for too high an ohmic value two sections are overlapped and both may be disconnected.

In accordance with my invention, this 35 defect is remedied by arranging the protective device for operation at different values of the ratio of the potential e to the current i . For example, two relays can be used, one of 40 which is adjusted for an ohmic value less than that of the section to be protected and is arranged to release an over-current relay set to operate after a predetermined period which for purposes of explanation may be assumed to be one second and the other of 45 which is adjusted for an ohmic value greater than that of the section and is arranged to release an over-current relay set to operate after a greater time period, for example, two 50 seconds. In order to avoid doubling the num- ber of relays, I provide in accordance with my invention a single relay, comprising a movable member which is arranged to take a position dependent on the relative values of the current and potential, such that the 55 line is disconnected in a predetermined time which remains fixed for any given value of current and is independent of the ratio of the potential to the current when the ratio lies within predetermined limits, the higher 60 of which is determined by or corresponds to the ohmic resistance, reactance or impedance of the section, and in a longer time when the ratio is greater than such higher limit. For a still greater value of the ratio, the 65 line is not disconnected at all. The number of ranges for the ratios is not limited and the ranges themselves are flexible. When two ranges are used as set forth above, the higher limit of the range giving the shorter 70 time should conform to the length of the line section to be protected. The higher limit of the range giving the greater time is somewhat restricted in order to avoid disconnection of a sound section next to a faulty section 75 but it may be chosen so large as to include substantially the resistances of the section to be protected and the next following section.

Inasmuch as the resistance may vary with 80 the character of the fault, that is, whether it is the result of a metallic contact between conductors or an arc-over, the relative values of the potential and current correspondingly vary even with the fault at the same location. This variation may effect the disconnection 85 of the wrong section but the uncertainty can be avoided by using the reactive component $e \sin \theta$ of the potential instead of the resistance component $e \cos \theta$, since the former remains substantially unaffected by the arc.

My invention will be better understood from the following description taken in connection with the accompanying drawing and its scope will be pointed out in the appended 95 claims.

In the accompanying drawing Fig. 1 illustrates partly in diagram and partly in perspective an embodiment of my invention and Fig. 2 illustrates schematically a dynamom- 100

eter type of moving coil ohm meter that may be used in carrying out my invention.

In the embodiment of my invention shown in Fig. 1, an electric line or circuit 1 is arranged to be controlled by a suitable circuit interrupter 2 through a trip coil 3, the circuit of which is controlled by a protective device comprising two elements such as an ohm meter 4 and an overcurrent time relay 5. These elements cooperate to provide the double range of control or time of release of the circuit interrupter 2 on the occurrence of a fault.

The ohm meter 4 may be of the induction disc type and as shown comprises two suitably shaped discs such as quadrants 6 and 7 which are mounted on a single shaft 8. Each disc has a driving element or magnet of the phase displacement type. The driving element of the disc 6 comprises cooperating current and potential windings 9 and 10 respectively arranged to be energized from the circuit 1 through current and potential transformers 11 and 12. Where it is desired to employ the reactance component of the potential, the constants of the circuits of the current and potential windings 9 and 10 are so chosen as to carry currents which are in phase when there is non-inductive load on the circuit.

The driving element for the disc 7 comprises cooperating current windings 13 and 14 connected to be energized from the current transformer 11. The displacement of the currents in these windings may be obtained in any suitable manner, as for example, by a resistance 15 connected in series with the winding 14.

If, now, K_1 and K_2 represent constants, $f_1(\phi)$ and $f_2(\phi)$ functions of the angular position or displacement from an arbitrary reference line of the discs 6 and 7, and i , e and θ the current and potential of the line 1 and the phase angle between them, then because of the shape of the discs and the construction and arrangement of the parts, the torques T_1 and T_2 on the discs 6 and 7 respectively are:

$$T_1 = K_1 e i \sin \theta f_1(\phi)$$

$$T_2 = K_2 i^2 f_2(\phi)$$

The shaft 8, being left to itself, comes to a position of rest or state of equilibrium through the equalization of the torques in an angular position which is dependent upon the relative values of the current and potential of the circuit, thus:

$$K_2 i^2 f_2(\phi) = K_1 e i \sin \theta f_1(\phi)$$

$$\frac{f_2(\phi)}{f_1(\phi)} = \frac{K_1 e i \sin \theta}{K_2 i^2}$$

$$F(\phi) = K \frac{e \sin \theta}{i}$$

Where it is desired to employ the resistance

component of the potential, the constants of the circuits of the current and potential windings 9 and 10 are so chosen as to carry currents displaced 90° in phase relation when there is non-inductive load on the circuit. In this case, in the above formulæ $\cos \theta$ will replace $\sin \theta$.

The over-current time element or relay 5 may be of any suitable type. This relay has its winding 17 in series relation with the line 1 through the current transformer 11. For purposes of illustration, the time action is shown as being obtained by a step-up gear drive 18 on a fan wheel 19. For controlling the circuit of the trip coil 3 in accordance with the combined action of the ohm meter 4 and the relay 5, relatively movable cooperating members such as contacts 20 and 21 are mounted on a pivot and arranged to be actuated by the relay 5.

In order to control the closing of the contacts 20 and 21 in accordance with the double ranges heretofore described, a member 22 is secured to the shaft 8 so as to be for certain angular positions of the shaft in the path of movement of the contacts 20 and 21. This movable member 22 may be of arcuate contour and as shown comprises two sections whose angular extents are designated A_1 and A_2 and which have different radii. Obviously, for a given current, relative movement of the contacts, that is to say, closure thereof, will occur more quickly when the longer radius section of the member 22 is in the path of movement of the contacts 20, 21, than when the short radius section is in this path. Thus, for any position of the member 22 within the angular range A_1 and a given current, the contacts will be closed in a shorter time than when the member 22 is within the angular range A_2 . Obviously, it is not necessary to have both contacts movable by the relay 5, since the member 22 could of itself constitute the contact 20. Closure of the contacts 20 and 21 can only occur when the shaft 8, the position of which is determined by the relative values of the current and potential of the circuit, sets the member 22 in the path of movement of the contacts 20, 21, that is for an angular range of movement of the shaft equal to the sum of A_1 and A_2 . The position of the shaft 8 for the angular range A_1 would be determined by the ohm meter for ohmic values less than that of the section to be protected, while for the angular range A_2 values greater than that of the section would govern.

The ohm meter 4 shown in Fig. 1 is of the induction disc wattmeter type but other types of ohm meter such as the moving coil type shown schematically in Fig. 2 may be used. This type comprises two fixed coils 24 and 25 which are arranged substantially perpendicularly to each other and a movable coil 26. The fixed coils 24 and 25 would be con-

nected to be energized respectively in accordance with the current i and the reactive component $e \sin \theta$ of the potential of the circuit and the moving coil 26 would be connected 5 to be energized in accordance with the current in the circuit. The sine component is obtained when with the non-inductive load on the circuit the currents in the fixed windings 24 and 25 are displaced by 90° .

10 By virtue of the magnetic forces existing between the fixed coils and the movable coil, the torques exerted thereon position the movable coil so as to establish equilibrium. The torques T_1 between the coils 24 and 26 and T_2 , 15 between the coils 25 and 26 are:

$$T_1 = K_1 i^2 \cos \phi$$

$$T_2 = K_2 e i \sin \theta \sin \phi$$

20 The angular position of the movable coil 26 resulting from the balancing of these torques is dependent upon the relative values of the current and potential of the circuit, thus:

$$25 K_1 i^2 \cos \phi = K_2 e i \sin \theta \sin \phi$$

$$\frac{\cos \phi}{\sin \phi} = \frac{K_2}{K_1} \frac{e i \sin \theta}{i^2}$$

$$30 \cot \phi = K \frac{e \sin \theta}{i}$$

What I claim as new and desire to secure by Letters Patent of the United States is:—

1. A protective device comprising a time 35 limit relay, an ohm meter and movable members respectively arranged to be actuated thereby, characterized by the fact that one of said members is arranged for movement in the path of movement of the other and is so shaped that for predetermined ranges of 40 movement different definite movements of the other are permitted.

2. A protective device comprising relatively movable cooperating contacts, an over-current time relay for actuating said contacts and an ohm meter having a member movable in the path of movement of said contacts characterized by the fact that said member is so shaped as to permit relative 50 movement of the contacts by the over-current relay in a time dependent on the current and the position of the member.

3. In combination with an electric circuit 55 and circuit interrupting means therefor, relay means comprising a winding connected to be energized in accordance with the current in said circuit and a winding affected by the potential of said circuit arranged to control said interrupting means in a predetermined time, and means for maintaining the time fixed for any given value of current independently of the ratio of the potential to the current when the ratio lies within predetermined limits and for permitting a longer

time when the ratio is greater than the higher of said limits.

4. In combination with an electric circuit and circuit interrupting means therefor, means for controlling said interrupting 70 means on the occurrence of a fault comprising a time limit relay and an ohm meter including means arranged to control the opening of said interrupting means in a predetermined time, which remains fixed for any 75 given value of current and is independent of the ratio of the potential to the current when the ratio lies within predetermined limits and in a longer time when the ratio is greater than the higher of said limits.

5. A protective device for an electric circuit comprising relatively movable cooperating contacts, a relay having a current responsive winding for actuating said contacts, and an ohm meter comprising a movable 85 member adapted to take a position dependent on the relative values of the current and potential of the circuit at the point where the device is located and arranged on the occurrence of a fault to take a position in the 90 path of movement of said contacts whereby to permit relative movement thereof by said relay in a predetermined time dependent on the current when the ratio of the potential to the current is less than a predetermined 95 value and in a longer time when the ratio is greater than such predetermined value.

6. In combination with an electric circuit, a protective device comprising relatively movable cooperating contacts, an over-current 100 relay for actuating said contacts, and an ohm meter having a movable member adapted to take a position dependent on the relative values of the current and potential of the circuit at the point where the device 105 is located, said member being constructed and arranged on the occurrence of a fault to take a position in the path of movement of said contacts dependent on the location of the fault whereby relative movement of the contacts is effected by the over-current relay in a time which is dependent on the current and is shorter, when the ratio of the potential to the current is less than a predetermined 110 value, than the time when the ratio is greater 115 than such predetermined value.

7. In combination with an electric circuit a protective device comprising relatively movable cooperating contacts and means for actuating said contacts comprising an over-current 120 relay and an ohm meter having a movable member adapted to take a position dependent on the relative values of the potential and current of the circuit, said member being mounted in the path of movement 125 of said contacts and shaped so that for a predetermined angular range of positions the time necessary to close the contacts is substantially constant for a predetermined value of current and for another predeter- 130

mined angular range the time is longer and substantially constant for the same value of current.

8. In combination with an electric line, a protective device comprising relatively movable cooperating contacts, and means for actuating said contacts comprising a time element relay and an ohm meter having a movable member adapted to take a position dependent on the relative values of the current and potential of the line at the point where the device is located and arranged to permit relative movement of said contacts by the time element relay only when the ratio of the potential to the current is within predetermined limits either side of the impedance of the line section with which the device is associated.

9. A protective device comprising relatively movable cooperating elements and means for controlling said elements including a time relay and an ohm meter and means controlled by said ohm meter for permitting the completion of the relative movement of said elements in a fixed time throughout one range in movement of the ohm meter and in different fixed time throughout another range in movement of the ohm meter.

10. In combination with an electric circuit and circuit interrupting means therefor, relay means comprising a winding connected to be energized in accordance with the current in said circuit and a winding affected by the potential of said circuit arranged to control said interrupting means in a predetermined time and means for maintaining the time fixed for faults within a predetermined distance of the relay means and for permitting a longer fixed time when faults occur at a greater distance from the relay means.

11. A protective device comprising relatively movable cooperating contacts and controlling means therefor including a time relay and an ohm meter and means controlled by said ohm meter for effecting a circuit controlling operation of said contacts in a fixed time throughout one range in movement of the ohm meter and in a different fixed time throughout another range in movement of the ohm meter.

12. A protective device comprising relatively movable cooperating contacts and controlling means therefor including a time relay and an ohm meter, and means controlled by said ohm meter for effecting a circuit controlling operation of said contacts in a fixed time throughout one range in movement of the ohm meter and in a different fixed time throughout another range in movement of the ohm meter, and for preventing circuit controlling operation when the movement of the ohm meter is outside one of said ranges.

In witness whereof, I have hereunto set my hand this 8th day of August, 1925.

65 JOSEF BIERMANNS.

Certificate of Correction

Patent No. 1,783,105.

Granted November 25, 1930, to

JOSEF BIERMANNNS.

It is hereby certified that error appears in the printed specification of the above numbered patent requiring correction as follows: Page 3, line 16, for the first line of formula "T=K₁i² cos φ" read $T_1=K_1i^2 \cos \phi$; and that the said Letters Patent should be read with this correction therein that the same may conform to the record of the case in the Patent Office.

Signed and sealed this 6th day of January, A. D. 1931.

[SEAL.]

M. J. MOORE,
Acting Commissioner of Patents.
